UNITED STATES PATENT OFFICE.

PIERRE STEPONAS VILLMONT, OF NEW YORK, N. Y.

DESIGN FOR A LAMP-STANDARD.

44,325.

Specification for Design.

Patented July 8, 1913.

Application filed February 17, 1913. Serial No. 749,063. Term of patent 7 years.

To all whom it may concern:

Be it known that I, PIERRE STEPONAS VILLMONT, a citizen of Russia, and resident of the city of New York, in the county of New York and State of New York, have invented a certain new, original, and ornamental Design for a Lamp-Standard, of which the following is a specification.

The drawing illustrates a vase-like shaped standard for a lamp, showing my new design.

I claim:

The ornamental design for a lamp standard, as shown.

Signed at New York, in the county of New York and State of New York this 14th day of May A. D. 1913.

PIERRE STEPONAS VILLMONT.
